RAZOR BLADE

Filed June 10, 1944

FIG. 1.

Joseph Albert Guimond
INVENTOR.

UNITED STATES PATENT OFFICE

2,364,525

RAZOR BLADE

Joseph Albert Guimond, Montreal, Quebec, Canada, assignor to Marie Florida Gisele Yvette Giguere (nee Guimond), Noranda, Quebec, Canada

Application June 10, 1944, Serial No. 539,650

6 Claims. (Cl. 30—351)

The invention relates to a razor blade as described in the present specifications and illustrated in the accompanying drawing that forms a part of same.

The invention consists essentially of the novel features of construction, as pointed out broadly and specifically in the claims for novelty following a description containing an explanation in detail of an acceptable form of the invention.

The objects of the invention are to devise a blade formed and contrived in its outline in length and width to insert in and complete the usefulness of the "Magazine razor blade holder" patented on the 27th day of June, 1944, under No. 2,352,538.

Another object is to provide a razor blade having in length, width and contour requirements necessary for insert purposes and moving action in the "Magazine razor blade holder" Patent No. 2,352,538.

A further object is a required razor blade indented in its contour adapted for insertion in the "Magazine razor blade holder," patented 27th day of June, 1944, under No. 2,352,538, completing its operating action on delivery of a blade to its shaving position.

With the foregoing and other objects in view which will appear as the description proceeds the invention consists of certain novel details of construction more fully described and pointed out in the claims, it being understood that changes in sizes of shoulders, tenons and mortise cuts may be made without departing from the spirit of the invention as claimed.

In the accompanying drawing the preferred forms of the invention have been shown.

In said drawing,

Figure 1 is a face inclined drawing of the razor blade.

Figure 2—this drawing is a view of a back portion end of the razor blade.

Figure 3 is a drawing showing one end of the razor blade.

It is, therefore, the purpose of this invention to provide a proper razor blade to complete the utility of the "Magazine razor blade holder" patented No. 2,352,538.

The same numerals of reference indicate the same parts of the various figures.

Referring to the drawing:

The razor blade is a flat steel body portion 1, the projecting extensions on its back are called shoulders 2 acting as rocking protection when inserted for use in the magazine holder. The three retreated parts 3 divided by the shoulders 2 are called the back or rear of the blade. At each end of the razor blade are located two tenon teeth 4. The cutting or shaving edge is 6 minus a square mortise notch 5 at each of 1st ends. The tenons or teeth are divided by a receded groove 7.

What I claim is:

15. 1. A razor blade of steel comprising a cutting edge with square mortise notches at each end, a rear portion in an adapted form to insert in a blade magazine holder, said rear portion having two extended shoulders to prevent rocking in the magazine holder, two tenon teeth at each end of the blade separated by a retreated groove.

20. 2. A razor blade of steel comprising a cutting edge with square mortise notches at each end of said cutting edge for gripping purposes in cooperation with the back receded corner ends of the blade.

25. 3. A razor blade body formed with two tenon teeth at each end, separated by a receded groove, two extended shoulders at the back and a cutting edge with square mortise notches at each end.

30. 4. A razor blade with retreated portion of back of blade ends and mortise notches at ends of the cutting edge, both retreated portion and mortise notches adapted to cooperate for a gripping action on the blade.

35. 5. A razor blade having a back with two extended shoulders, its cutting edge cut at each end by square mortise notches, each end of the blade terminated with two square tenon teeth and a receded groove between said tenon teeth.

40. 6. A razor blade body, contrived in its contour with two back shoulders, four tenon teeth, a separating receded groove and a cutting edge with square notches at its corners.

45. JOSEPH ALBERT GUIMOND.
